UNITED STATES PATENT OFFICE.

WILLIAM J. MORRISON AND JOHN C. WHARTON, OF NASHVILLE,
TENNESSEE.

CANDY-MACHINE.

SPECIFICATION forming part of Letters Patent No. 717,756, dated January 6, 1903.

Application filed May 12, 1902. Serial No. 106,923. (No model.)

To all whom it may concern:

Be it known that we, WILLIAM J. MORRISON and JOHN C. WHARTON, citizens of the United States, residing at Nashville, in the 5 county of Davidson and State of Tennessee, have invented a new and useful Candy-Machine, of which the following is a specification.

Our invention relates to improvements in 10 candy-machines in which a rotative perforated vessel is supplied with an electrically-heated band or coil of suitable metal.

The objects of our improvement are to obtain a candy in the form of fine filaments or 15 threads, as well as a solid form of stick-candy. We attain these objects by the mechanism illustrated in the accompanying drawings, in which--

Figure 1 is a vertical section of the machine 20 as mounted upon a rotative shaft or spindle. Fig. 2 is a plan view of the lower portion of the vessel proper and the corrugated heating-band with the electrical connections.

Similar letters refer to similar parts in both 25 of the figures.

A A' represent, respectively, the lower and 30 upper parts of the containing vessel, having perforations or apertures at T T. The parts A and A' are held together by posts P P, by 35 which the apertures T T may also be regulated as to width of openings.

B B represent a corrugated band of metal 40 having such electrical resistance as to become heated by the passage of a current of electricity through it. This band may be replaced by a coiled wire or other suitable form of the resistive metal referred to above. The band B has at its extremities wires or conductors M M', connecting it through suitable 45 insulating material, as O, O', and G, with commutators I I', and the commutators receive the electricity from any suitable source through conductors L L', joined to the "brushes" H H', which are in sliding contact with the sleeves or commutators I I'.

The vessel A A' is secured to the tubular insulator G by means of the internal and external screws E and F, and the tubular part 50 of G is mounted on the shaft or spindle K, which shaft is rotatable, being the axis of an

electric or other motor, not otherwise shown in the illustrations.

The vessel A A' carries a grater R, attached to the rim of its upper portion A'.

The band B is supported by suitable pins 55 S S, held in place between A and A'.

The wires or conductors M M' may for the sake of convenience in taking apart or putting together be passed centrally through the screws E and F into their positions inside of 60 the vessel A A', proper insulation being supplied as the case demands.

In operation granulated sugar C is poured into the vessel A A' through a central opening D, the motor carrying the shaft K is 65 started, and the electric current is turned on through the conductors L L', brushes H H', commutators I I', conductors M M', and resistance coil or band B B. The band B B being heated to a sufficient degree, which is 70 controlled by a rheostat, (not shown in the drawings,) causes the sugar C to melt, and the centrifugal force, due to the rotation of the vessel A A', expels the melted sugar through the apertures T T in line of arrows N in the 75 form of silk-like threads, or by regulating the heat, form of heater, and receptacle a hard variety of stick-candy may be made. Since the molten sugar becomes more fluid at a higher temperature, its tendency to form 80 threads is lessened at the increased heat, and the molten sugar may be received into a receptacle placed very near to the rotating vessel, so as to confine the heat and receive the liquid sugar in its molten condition on the 85 surface of a cylindrical or polygonal receptacle, which chills, forming "sticks" or bars of such shapes as the receptacle may be made to give it.

Grated fruits, &c., may be thrown into the 90 candy by holding them against the grater R while the machine is in motion.

The admixture of the grated material with the fibrous material is effected in various ways—as, for instance, by a deflecting-flange 95 on the outer edge of the grater, by lessening the speed of rotation, or by raising the vessel containing the fibrous material during the said time of rotation.

Having described our invention, what we 100

claim as new, and desire to secure by Letters Patent, is—

1. The combination, in a candy-machine, of a rotative, circumferentially-perforated vessel A A, and an electrically resistive band or heater, B, connected to a source of electricity, substantially as shown and for the purpose set forth.

2. The combination, in a candy-machine, of a rotative, circumferentially-perforated vessel A A, heater B, and a grater R, sub-

stantially as shown and for the purpose set forth.

In testimony whereof we have signed our names to this specification in the presence of 15 two subscribing witnesses.

WILLIAM J. MORRISON.
JOHN C. WHARTON.
